UNITED STATES PATENT OFFICE.

WALTER O. SNELLING, OF PITTSBURGH, PENNSYLVANIA, ASSIGNOR TO AMERICAN GASOL COMPANY, OF PITTSBURGH, PENNSYLVANIA, A CORPORATION OF WEST VIRGINIA.

PROCESS OF REFINING NATURAL-GAS GASOLENE.

1,056,845.

Specification of Letters Patent.

Patented Mar. 25, 1913.

Application filed January 29, 1912. Serial No. 674,038.

To all whom it may concern:

Be it known that I, WALTER O. SNELLING, a citizen of the United States, residing at Pittsburgh, in the county of Allegheny and State of Pennsylvania, have invented certain new and useful Improvements in Processes of Refining Natural-Gas Gasolene, of which the following is a specification.

My invention relates to a process for refining a mixture of condensable vapors or gases, such as the mixture of vapors or gases resulting from the vaporization of what is known as "natural gas gasolene." This gasolene contains, in addition to the hydrocarbons, such as butane, pentane, hexane and heptane found in ordinary gasolene, lighter hydrocarbons of the paraffin series, such as ethane and propane, and it is the object of my invention to separate from the mixture 20 of vapors or gases, these lighter hydrocarbons and to simultaneously obtain fractions of higher boiling point and of more or less definite composition.

It is a further object of the invention to obtain the most volatile ingredient or mixture directly in the form of a liquid gas under pressure. If a liquid containing several volatilizable ingredients be vaporized in a closed vessel, the boiling points, or the 30 limits of temperature at which each ingredient will remain liquid, gradually rise as the pressure increases, but the rates at which the boiling points rise as the pressure increases, are not uniform, the boiling points 35 of the more volatile ingredients rising more rapidly than the boiling points of the less volatile ingredients. Thus, at high pressure, by which I mean, even for liquids of low boiling point, a minimum pressure of 40 two or three atmospheres, the boiling points of the ingredients are far more widely separated than at low pressures, such as those approximating one atmosphere.

By my process, a liquid containing several volatile ingredients is heated to a temperature sufficient to completely volatilize all of the ingredients, the vapors or gases being kept under maintained pressure, the pressure being so high that the boiling points 50 of the several ingredients will be widely separated, and then each ingredient, or a fraction containing several ingredients, is separately condensed, at a temperature slightly below the boiling point, at the high

pressure to which the mixture is subjected, 55 of that particular ingredient or fraction.

In the drawings—Figure 1 is an elevation of the still; Fig. 2 is a section of one of the condensing sections; and Fig. 3 is a section of the vaporizing portion of the still. Fig. 4 60 is a horizontal section on plane 4—4 of Fig. 3; Fig. 5 is a vertical section on plane 5—5 of Fig. 4; and Fig. 6 is a horizontal section on plane 6—6 of Fig. 2.

The refining apparatus consists of a vaporizer A, and condensing sections B, C, D. The vaporizer A is heated by a steam coil 1. The gasolene is admitted through pipe 2, and is discharged through the perforated spray ring 3 over coil 1. 4 is a wooden filling piece. The unvaporized residue of higher boiling point hydrocarbons, or unvolatilized ingredients are removed through pipe 6.

As will be apparent from Figs. 4 and 5, 75 the base piece 50 is provided with a passage 60 for gasolene, to which passage pipe 2 is connected; with passages 63, 64 to which the steam supply and discharge pipes 61 and 62 are connected; and with a passage 65, 70 connected to pipe 6 for discharging residual material.

The condensing sections B, C, D, are alike in construction except that the upper section has an inwardly concaved head 15 of 80 boiler plate.

Each of the condensing sections consists of a body portion of steel pipe, having screwed thereon a top ring 7 and bottom ring 8, each of cast iron and provided with 90 the necessary bolt holes. 9 are separating pieces of cast iron forming the top of a lower section and the bottom of an upper section, each having passages 54, 55 therethrough to which are connected pipes 51, 52 95 for supplying and discharging cooling fluid; a central passage 53, to which is connected a pipe 13; and a passage 56 for delivering the condensate to the pipe 10.

Tight joints are secured by providing 100 rings 11 to fit into corresponding grooves 12, with interposed lead gaskets, the various sections being bolted together so that a gas tight tower, capable of standing a high internal pressure, such as 900 lbs. to the square 105 inch, is produced.

The vapors are delivered from one section to the next through pipes 13, against wooden

filler blocks, and are thus compelled to pass over the cooling coils. Each of the various pipes referred to may be provided with such cocks or valves as are necessary.

5 In carrying out the process, the natural gas gasoline is sprayed over the coil 1, which is heated by superheated steam at a temperature sufficient to produce by the vaporization of the gasoline a high pressure, say 900 10 lbs., throughout the apparatus.

10 The vapors produced in the vaporizer A pass up through pipe 13, into condenser section B, and over the coil 16 therein, through which hot water is passing, and that portion of the mixture condensable at the pressure in the chamber and at the temperature of the coil, is condensed and passes out through pipe 10, to which is, of course, connected a suitable delivery pipe.

15 20 The coil in the chamber C carries warm water and that in chamber D, cold water.

25 Fractions containing the hydrocarbons of higher boiling point will be condensed and collected from sections C and B; that from section C may be gasoline of about 108°, and that from section B, gasoline of about 80°. I do not wish to be understood as limiting the process to these particular qualities of product, as it is evident that by varying the temperatures of the cooling coils 30 products of any desired degree may be obtained.

35 As the condensation is effected under very high pressure, the temperatures of the cooling coils may be much higher than those used at atmospheric pressure, thus avoiding the inconvenience and expense due to the use of such low temperature refrigerants as liquid ammonia, cold water being sufficient 40 to effect the condensation of the ethane and propane in the upper section of the still, from which there is directly obtained under high pressure a liquefied gas, which may be collected in suitable receptacles.

45 45 The various liquids delivered from the va-

rious pipes are collected into suitable receptacles, which it is unnecessary to illustrate as the conditions required to properly handle the materials will be obvious to those skilled in the art.

50

I claim:

1. The process of separating by fractional condensation a mixture of condensable gases or vapors which consists in subjecting a heated mixture of such gases or vapors under pressure in excess of two atmospheres to the condensing action of a series of condensers, each of which is maintained at a temperature just below the boiling point, at the high pressure to which the mixture is subjected, of the constituent condensed thereby.

55

2. The process of separating by fractional condensation the highly compressed heated vapors of natural gas gasoline which consists in subjecting such vapors under pressure in excess of two atmospheres to the condensing action of a series of condensers, each of which is maintained at a temperature just below the boiling point, at the high pressure to which the vapors are subjected, of the constituent condensed thereby.

60

3. The continuous process of refining by fractional condensation the highly compressed heated vapors of natural gas gasoline which consists in continuously subjecting such vapors to the action of a series of condensers, each of which is maintained at a temperature just below the boiling point, at the high pressure to which the mixture is subjected, of the constituents condensed thereby and continuously removing the condensed constituent.

65

70 In testimony whereof I affix my signature in presence of two witnesses.

75 WALTER O. SNELLING.
